(57) **CLAIM**

The ornamental design for a display screen or portion thereof with graphical user interface, as shown and described.

DESCRIPTION

FIG. 1 is a front view of a display screen or portion thereof with graphical user interface showing my new design; and, FIG. 2 is a second embodiment thereof.

The broken lines showing a display screen illustrate portions of the article, and form no part of the claimed design.

1 Claim, 1 Drawing Sheet
